CIGARETTE CHOKING OR SNUFFING
DEVICE FOR ASH TRAYS

Eugene Jacob, Trenton, N. J.

Application October 21, 1932, Serial No. 638,982

7 Claims. (Cl. 131—51)

This invention relates to an improved cigarette choking or snuffing device for use in connection with ash trays, for smoking stands and the like, and the purpose thereof is to provide a device 5 of this kind which is applicable to any kind of an ash tray, such as may rest on a table or other support and movable from one place to another thereon, or whether it is mounted on a humidor or a stand.

10 Ash trays which have depressions with solid bottoms for receiving the lighted end of a cigarette, for the purpose of choking or snuffing the same out are common. However in this type of device the depressions become filled with the 15 cigarette stub or parts of it, then it is necessary to soil one's fingers to remove the stubs and place them in the tray.

Another purpose of this invention is to provide means for actuating movable bottoms in the 20 choking or snuffing out depressions, so that subsequently to choking or snuffing out the lighted end of the cigarette, it is possible to manually 25 actuate said means, impart movement to the movable bottoms, and therefore discharge the stub, which will automatically fall in the ash tray.

Another purpose is to provide means for attaching the ash tray to a humidor or a stand.

In the drawings:—

30 Figure 1 is a plan view of an ash tray, showing cigarette or cigar holders thereon and illustrating the choking cavities or depressions and the means for actuating the movable bottoms therein.

35 Figure 2 is a vertical sectional view on line 2—2 of Figure 1.

Figure 3 is a view in side elevation.

40 Figure 4 is an enlarged detail view of the means for removably attaching the tray to a humidor or other container.

Figure 5 is a sectional view on line 5—5 of Figure 2.

45 Figure 6 is a detail view of a portion of the margin of the tray and a portion of the margin of the wall of the container 2, showing more clearly the construction of the means for guiding the lateral bent ends 14 of the arms 13 of the strip 10 through the enlarged portions 12 of the slots, when the plate 5 is in an unlocked position.

50 Referring to the drawings 1 identifies the tray, which in the present instance is supported upon a container 2, the central part of which has a compartment 3 for an absorbent material adapted to be saturated with water acting as a humidor for cigarettes or cigars which may be arranged

in the container. The casing of the container 2 as well as the ash tray may be made of any suitable material such as bakelite, porcelain, glass, metal and plastic material of all kinds. The ash tray may be any suitable shape, preferably in the present instance circular as shown, and it has holders 4 for the reception of lighted cigarettes or cigars.

5 The ash tray has a depending flange 2a which fits down over the casing of the container 2, and at diametrical opposite points adjacent this flange are bosses 2b provided with bushings 2c. In addition to the actual bottom 2d of the tray a circular plate 2e is secured to the bosses by means of screws 2g, said screws entering the bushings 2c, which are frictionally fitted or cemented in the bosses. The cylindrical wall of the container 2 at diametrical opposite points have notches 2h, which straddle the bosses, the notches being so located as to guide the tray into its position on 10 the container, for the purpose as hereinafter stated. A plate 5 which is circular is secured by means of a screw 6 to a central standard 7 which rises from the center of the humidor 2. The bottom of the container 2 has a threaded 15 bore 8, in which a standard may be connected 20 for supporting the container.

25 The plate 5 is provided with slots 9, as shown in the plan view, and a U shaped strip 10 has its arms engaging through the slots 9. The arms 30 of the U shaped strip 10 engage through the circular plate 2e, in order that the right angle extremities of the arms may pass through the slots 9 of the plate 5. In other words the larger 35 portions 12 of the slots, when in position to receive the right angle extremities of the arms of the U shaped strip 10 the larger portions 12 of the slots are in radial register with the notches 2h of the wall of the container 2, so that the tray may fit down onto the container, and in this 40 instance the right angle extremities 14 of the arms 13 will pass through the larger portions of the slots 9 of the plate 5, and as immediately 45 hereinafter stated the ash tray may be locked to the container. The plate 5 is capable of rotation slightly through the medium of a lever 11. In other words by moving the lever 11 slightly the larger portions 12 of the slots as shown in the plan view may be positioned so that the 50 arms 13 of the U shaped strip 10 may pass through the slots, and then by rotating the plate 5 back the angular bent ends 14 may engage under the plate, and thereby lock the ash tray to the container. By having the notches 2h in radial register with the larger portions 12 of the slots 9

when the plate 5 is in unlocked position it is possible to guide the tray in position and held in such position by the notches 2h straddling the bosses 2b allowing the lateral bent ends 14 to 5 pass through the larger portions 12 of the slots 2.

The central part of the ash tray has an up-standing hollowed out portion 15 provided with cylindrical ends 16, in which plungers 17 are guided, the normal positions of the plungers being down. A boss 18 rises from the hollowed out portion 15 and in the bottom of the boss a button 19 is positioned. This button is threaded at 20 to the U shaped strip 10, to secure the strip in the hollowed out part 15. The button also 15 acts as a guide for the reduced section 21 of the plunger 22, which is spring tensioned by means of a spring 23 mounted in the boss 18. The reduced section 21 of the plunger is threaded to the larger portion of the plunger as at 24. The 20 lower end of the reduced section of the plunger has a U shaped terminal 26 in which a pivot pin 28 is mounted, connecting the adjacent ends of the two links 27 to the plunger. These links engage through slots 28 formed in the arms of the 25 U shaped strip 10, and the remote ends of the links are connected by slots and pins 29a and 29 to the lower ends of the plunger 17, so that by pressing the plunger 22 downwardly the plungers 17 (which constitute movable bottoms for the 30 chambers 16a formed in the cylindrical ends 16) will raise and discharge the choked or snuffed out cigarette. The slots 29a are inclined downwardly away from each other, acting to move the plungers or bottoms 17 without binding.

35 When finishing smoking a cigarette, the burnt end of the cigarette can be engaged in either of the cylindrical chambers 16a while the plungers 17 are in their lowermost positions. Obviously the fire on the end of the cigarette is choked out 40 and then by depressing the plunger 22, the plungers 17 will raise and discharge the cigarette butt out into the ash tray.

The invention having been set forth, what is claimed is:

45 1. The combination with an ash tray having a hollowed out portion with open ended chambers at its ends, of a support for the tray, means for removably attaching the tray to the support, movable bottoms in the open ended chambers, and 50 tilttable means housed in the hollowed out portion of the tray and connected to the movable bottoms at right angles thereto for causing the discharge of cigarette stubs.

55 2. The combination with an ash tray having a hollowed out portion provided with open ended chambers at its ends, movable bottoms in the open ended chambers, and tilttable means housed in the hollowed out portion and connected to the movable bottoms for moving the bottoms upwardly 60 for discharging cigarette stubs.

55 3. The combination with an ash tray having a hollowed out portion provided with open ended chambers at its ends, movable bottoms in the open ended chambers, and means housed in the hollowed out portion and connected to the movable

bottoms for moving the bottoms upwardly for discharging cigarette stubs, and a manually actuated device at right angles to and connecting with said means for operating the latter.

4. The combination with an ash tray having a hollowed out portion provided with open ended chambers at its ends, movable bottoms in the open ended chambers, and means housed in the hollowed out portion and connected to the movable bottoms for moving the bottoms upwardly for 10 discharging cigarette stubs, and a manually actuated spring tensioned device for operating said means.

5. The combination with an ash tray having a central hollowed out portion provided with 15 open ended chambers at its ends, of a support for the tray, said support including a plate having diametrically opposite slots, certain ends of which have enlargements, and means carried by the tray and insertable through the enlargements of 20 the slots and the plate being movable to locate said means under the smaller portions of the slots, thereby attaching the tray to the support, movable bottoms in the open ended chambers, means in the hollowed out portion for causing 25 movement of the bottoms upwardly to discharge cigarette butts, and a device manually actuated and spring tensioned for operating said means.

6. The combination with an ash tray having a central hollowed out portion provided with open 30 ended chambers at its ends, of a support for the tray, said support including a plate having diametrically opposite slots, certain ends of which have enlargements, and means carried by the tray and insertable through the enlargements of the 35 slots and the plate being movable to locate said means under the smaller portions of the slots, thereby attaching the tray to the support, movable bottoms in the open ended chambers, pivotally connected links fulcrumed mid way their 40 ends, the remote ends of the links being connected to the movable bottoms, and means connected to the adjacent ends of the links for tilting them for moving the bottoms upwardly for 45 discharging cigarette butts.

7. A combination with an ash tray having a central hollowed out portion provided with open ended chambers at its ends, said chambers having movable bottoms, of a support comprising a container for smoking material, said container 50 having a cover therefor, said cover having concentric diametrically opposite slots, and a plate secured to the container and positioned under the cover and having concentric diametrically opposite slots, certain ends of which have concentric enlargements, means carried by and concentric with the center of the tray provided with lugs insertable through the enlargements of the 55 slots, said means being turnable to position the lugs out of registry with the enlargements of the 60 slots whereby the lugs may be arranged under the smaller portions of the slots, said tray and the wall of the container having means to guide the lugs to enter the enlargements of said slots.
